DESIGN FOR AN OIL BURNING COOK STOVE

William T. Bradbury, Kankakee, Ill., assignor to
Florence Stove Company, Gardner, Mass., a
corporation of Massachusetts

Application February 25, 1935, Serial No. 55,595

Term of patent 7 years

To all whom it may concern:

Be it known that I, William T. Bradbury, a citizen of the United States, residing at Kankakee, in the county of Kankakee and State of Illinois, have invented a new, original, and ornamental Design for an Oil Burning Cook Stove, of which the following is a specification, reference being had to the accompanying drawing, forming part thereof.

The figure is a perspective view of an oil burning cook stove showing my new design, both ends of the stove being substantially the same.

I claim:

The ornamental design for an oil burning cook stove substantially as shown and described.

WILLIAM T. BRADBURY.
